[57] **CLAIM**

The ornamental design for a ticket dispensing machine, as shown and described.

DESCRIPTION

FIG. 1 is a perspective view of the ticket dispensing machine showing my new design;

FIG. 2 is a top plan view thereof;

FIG. 3 is a left side elevation view thereof;

FIG. 4 is a rear elevation view thereof; and,

FIG. 5 is a bottom plan view thereof.

The broken line showing of the informational panel on FIG. 1 is for illustrative purposes only and forms no part of the claimed design.
